Application August 1, 1957, Serial No. 675,610

3 Claims. (Cl. 179—171)

This invention relates to electrical circuits for reversing the polarity or phase of electric signals.

There is a frequent need for electrical circuits that will provide an output signal that is opposite in polarity or phase, but is otherwise identical, to an input electric signal. An ordinary grounded-cathode vacuum-tube amplifier stage provides an output signal of opposite phase to the input signal, but such amplifier stages usually have a low-frequency cutoff below which they fail to operate properly, and therefore they are not suitable for reversing the polarity of signals having substantial low-frequency and direct-current components. Certain direct-coupled amplifiers have previously been devised that theoretically have no low-frequency cutoff, and are operable down to the zero frequency (direct current), but such previous circuits commonly lack some or all of several desirable characteristics, including zero output voltage for zero input voltage, stability and freedom from drift, circuit simplicity and ruggedness, and operating characteristics that are substantially independent of load resistance.

Briefly stated, according to certain of its aspects, this invention provides an improved polarity reversing circuit that combines desirable operating characteristics with circuit simplicity and ruggedness. The improved circuit is a three-terminal active network having input, output and common terminals. Responsive to an input voltage applied between the input and common terminals, an output voltage of the opposite polarity is provided between the output and common terminals.

The circuit includes a cathode follower having anode connections to a positive voltage supply, and cathode connections to a negative voltage supply, so that the cathode potential may vary through a range of positive and negative values relative to the potential of the common terminal. The output terminal is connected to the cathode of the cathode follower. A resistance voltage divider is connected between the input terminal and an adjustable tap on a cathode resistor of the cathode follower. The voltage divider is provided with a center tap. A phase-inverting voltage amplifier is connected between this center tap and the control grid of the cathode follower, so that any small positive-going change in the potential of the center tap causes a much larger negative-going change at the control grid of the cathode follower, and vice versa.

As a result, any positive-going change in the potential of the input terminal (relative to the common terminal) causes an equal negative-going change in the potential of the output terminal, and vice versa. The adjustable tap provides a calibrating means that can be adjusted to make the output voltage equal to zero when the input voltage equals zero. This calibrating adjustment is usually required only when the apparatus is initially set up, or when a vacuum tube is changed. Once the circuit is calibrated, it is exceptionally stable, is substantially drift-free, and operates with low distortion from zero

2

frequency (direct current) through the audio frequency range.

The invention may be better understood from the following illustrative description and the accompanying drawing. The scope of the invention is pointed out in the appended claims.

In the drawing, the single figure is a simplified circuit diagram of an improved polarity reversing circuit.

Referring to the drawing, the polarity reversing circuit illustrated includes an input terminal 1, an output terminal 2, and a common terminal or connection 3, which may be circuit ground. In its preferred form, the circuit includes two vacuum tube sections 4 and 5, which may be the two halves of a twin triode vacuum tube, such as a type 12AT7 tube. Each vacuum tube section has an anode, a control grid and a cathode, as is indicated in the drawing by conventional symbols.

A positive voltage supply 6 is connected to supply a fixed positive potential (+300 volts, for example) 20 relative to common terminal 3. A negative voltage supply 7, which preferably includes a voltage regulator tube 8 and dropping resistor 9, is connected to supply a fixed negative potential (-150 volts, for example) relative to common terminal 3. For example, regulator tube 8 may be a type OA2 tube and resistor 9 may have a resistance of 4000 ohms, while the unregulated voltage across 7 is about -250 volts. The negative voltage supply preferably is regulated with a voltage regulator tube, as shown, because the stability of the negative potential is critical to drift-free operation of the circuit. However, this is the only critical circuit value, and moderate variations in other circuit values, such as to be expected with ordinary circuit components, have negligible effect upon the circuit operation. Therefore, in contrast to most direct-coupled electronic circuits, stability and substantially drift-free operation in the present circuit are assured simply by regulating the value of one critical voltage.

40 Vacuum tube section 4 is connected in a conventional phase-inverting direct-coupled amplifier stage, and vacuum tube section 5 is connected in a cathode follower stage. The anode of tube section 5 is connected directly to positive voltage supply 6. The cathode of tube section 5 is connected through a potentiometer 10 and a resistor 11, in series, to the negative voltage supply, as shown. For example, the total resistance of potentiometer 10 may be 1000 ohms, and the resistance of resistor 11 may be 18,000 ohms. There is a direct circuit connection 12 between the cathode of tube section 5 and output terminal 2.

45 Potentiometer 10 has a conventional adjustable tap 13. Between this adjustable tap and input terminal 1, there is connected a resistance voltage divider consisting of two resistors 14 and 15 connected in series, as shown. Preferably, the two resistors 14 and 15 have equal resistance values, 270,000 ohms each, for example. The circuit junction 16 between the two resistors is the center tap of the voltage divider.

50 The anode of tube section 4 is connected to the positive voltage supply circuit through a load resistor 17. The control grid of tube section 4 is connected to center tap 16 of the voltage divider. The cathode of tube section 4 is connected directly to common terminal 3, which may be circuit ground.

55 Another resistance voltage divider, consisting of two resistors 18 and 19 in series, is connected between the anode of tube section 4 and the negative voltage supply. The circuit junction between resistors 18 and 19 is connected to the control grid of tube section 5. By way of example, resistor 17 may have a value of 47,000 ohms, resistor 18 may have a value of 560,000 ohms, and resistor 19 may have a value of 680,000 ohms. This

divider supplies to the control grid of tube section 5 voltage changes in phase with voltage changes at the anode of tube section 4, while maintaining the control grid potential nearer ground potential for proper operation of the cathode follower stage. This completes the circuit.

The circuit may be calibrated as follows. Input terminals 1 and 3 are connected directly together, by means of a jumper or the like, so that the input voltage between terminals 1 and 3 is held at zero. A voltmeter is connected to measure the output voltage between terminals 2 and 3. Now the position of tap 13 is adjusted. As tap 13 is moved upward, the control grid of tube section 4 becomes more positive, and tube section 4 conducts more current. This causes the anode of tube section 4 and the control grid of tube section 5 to become more negative, whereupon tube section 5 conducts less current. This causes the potential of output terminal 2 to become more negative. Conversely, when tap 13 is moved downward the potential of output terminal 2 becomes more positive. A position of tap 13 can be found at which the measured voltage between terminals 2 and 3 is zero, and at this position of tap 13 the circuit is properly calibrated. Because the circuit is quite stable, re-calibration is usually required only when the vacuum tube is replaced. After calibration has been completed, the jumper and voltmeter are removed, and the circuit is ready for operation.

It should be appreciated that the resistance between the cathode of tube section 5 and adjustable tap 13 is only a small fraction of the total resistance between cathode 5 and the negative voltage supply. With zero input and output voltages, the total voltage drop across potentiometer 10 and resistor 11 in series is 150 volts, this being the voltage that is provided by the regulated negative voltage supply including the voltage regulator tube 3. The voltage drop between the cathode of tube section 5 and tap 13 must have twice the magnitude of the negative bias that must be supplied to tube section 4 to balance and calibrate the circuit. Since the required negative bias is only a few volts, only a small fraction of the total voltage drop across potentiometer 10 and resistor 11 is required. Therefore, the resistance of resistor 11 preferably is considerably larger than the total resistance at potentiometer 10, and, except for the bias and calibration functions herein described, the resistance between the cathode of tube section 5 and potentiometer 13 has little effect upon the circuit operation.

Therefore, with respect to its dynamic operation, the circuit operates essentially as though resistor 15 were connected directly to the cathode of tube section 5. In fact, the small difference in dynamic operation due to the resistance between the cathode of tube section 5 and tap 13 acts to make the output voltage very slightly larger in magnitude than it would be otherwise, and this tends to compensate for the finite gain of the amplifier stage (tube section 4), which tends to reduce the output voltage, so that differences in the magnitudes of the input and output voltages are kept quite small (in the order of one percent), and the circuit operates with very low distortion over a range of input voltages between +12 volts and -12 volts.

Assume that there is applied between input terminal 1 and common terminal 3, from any suitable source, an input voltage that varies between +12 volts and -12 volts. Whenever the instantaneous potential of terminal 1 becomes more positive with respect to terminal 3, the control grid of tube section 4 becomes more positive. Since tube section 4 is connected as a phase-inverting amplifier, the anode of tube section 4 and the control grid of tube section 5 become more negative. Tube section 5 operates as a cathode follower, and output terminal 2 and tap 13 become more negative. This makes the potential of the control grid of tube section 4 more negative, and thus opposes the positive-going change caused by an increase in the potential of terminal 1.

In actual operation, because of the considerable loop gain of the circuit, changes in the potential of center tap 16 are relatively small, and any change in the potential of terminal 1 is substantially balanced by an almost equal change in the potential of tap 13. Because the loop gain is finite, there must be some small change in the potential of center tap 16 to operate the circuit, and the potential changes at adjustable tap 13 must be slightly smaller in magnitude than the potential changes at input terminal 1. However, the difference is small, and even this small difference tends to be compensated for by the voltage drop across the upper part of potentiometer 10 between the cathode of tube section 5 and tap 13. This voltage drop causes the potential change at output terminal 2 to be slightly larger (two or three percent) than the potential changes at tap 13. Thus, the over-all accuracy of the circuit is very good, and the potential changes of output terminal 2 are almost exactly equal in magnitude (within one or two percent) but of opposite polarity to the potential changes at input terminal 1.

It is thus apparent that the circuit illustrated and described operates with exceptionally low distortion and provides an output signal between terminals 2 and 3 that is equal in magnitude, but opposite in polarity and phase, to an input signal provided between terminals 1 and 3. The circuit is operable from zero frequency (direct current) through at least the audio frequency range, and can be designed for operation at even higher frequencies. Because the output is taken from the cathode of the cathode follower stage, the output impedance is low, and the operating characteristics are substantially unaffected by reasonable variations in the load impedance. There is only one simple calibration adjustment (to set the zero level) and this calibration adjustment need ordinarily be made only when a tube is changed, since the circuit is exceptionally stable and drift-free. The only critical circuit value is the stability of the negative voltage supply, which is easily assured by the use of a good voltage regulator tube.

It should be understood that this invention in its broader aspects is not limited to the specific example herein illustrated and described, and that the following claims are intended to cover all changes and modifications within the true spirit and scope of the invention.

What is claimed is:

1. In an electrical circuit, the combination of an input terminal, an output terminal, a common terminal, a positive voltage supply connected to provide a fixed positive potential relative to said common terminal, a negative voltage supply connected to provide a fixed negative potential relative to said common terminal, a cathode follower having anode circuit connections to said positive voltage supply, having a control electrode, and having cathode circuit connections to said negative voltage supply, a direct circuit connection between said cathode circuit connections and said output terminal, a resistance voltage divider connected between said cathode circuit connections and said input terminal, said voltage divider having a tap, and a direct-coupled, phase-inverting amplifier connected between said tap and said control grid.

2. A polarity reversing circuit comprising an input terminal, an output terminal, a common terminal, a positive voltage supply connected to provide a fixed positive potential relative to said common terminal, a negative voltage supply connected to provide a fixed negative potential relative to said common terminal, first and second vacuum tube sections each having an anode, a control grid and a cathode, a load resistor connected between the anode of said first section and said positive voltage supply, means connecting the anode of said second section to said positive voltage supply, means connecting the cathode of said first section to said common terminal, potentiometer means connected between the cathode of said second section and said negative voltage supply, said

potentiometer means having an adjustable tap, a first resistance voltage divider connected between said adjustable tap and said input terminal, said first voltage divider having a tap connected to the control grid of said first vacuum tube section, a second resistance voltage divider connected between the anode of said first vacuum tube section and said negative voltage supply, said second voltage divider having a tap connected to the control grid of said second vacuum tube section, and a direct circuit

connection between the cathode of said second vacuum tube section and said output terminal.

3. A polarity reversing circuit as defined in claim 2, wherein said negative voltage supply comprises a voltage regulator tube for stabilizing the value of said negative potential, whereby the polarity reversing circuit is made substantially drift-free.
